UNITED STATES PATENT OFFICE.

JULIUS JOHN MOJONNIER AND HARLEY RAY PHILLIPS, OF OAK PARK, AND HENRI B. WARREN, DECEASED, LATE OF OAK PARK, ILLINOIS; BY LEWIS W. WARREN, ADMINISTRATOR, OF OAK PARK, ILLINOIS, ASSIGNORS TO MOJONNIER BROS. CO., OF CHICAGO, ILLINOIS, A CORPORATION OF ILLINOIS.

ICE-CREAM-PACKAGING MACHINE.

Application filed July 13, 1922. Serial No. 574,642.

To all whom it may concern:

Be it known that JULIUS JOHN MOJONNIER, HARLEY R. PHILLIPS, and HENRI B. WARREN, the latter deceased, LEWIS W. WARREN being the administrator of his estate, all citizens of the United States, and residents of Oak Park, in the county of Cook and State of Illinois, have invented certain new and useful Improvements in Ice-Cream-Packaging Machines, of which the following is a specification.

This invention relates to ice cream packaging machines wherein multiple layers of the same or differing colors or flavors of ice cream are packed in cartons or containers, and has for its object the provision of a machine of this character which will simultaneously measure and deliver the ice cream, of the same or differing colors or flavors to the cartons or containers automatically fed thereto.

With the above and other objects in view, as will be apparent, this invention consists in the construction, combination and arrangement of parts all as hereinafter more fully described, claimed and illustrated in the accompanying drawings wherein:

Fig. 1 is a side elevation of a machine constructed in accordance with the present invention.

Fig. 2 is a similar view taken from the opposite side of the machine to Fig. 1.

Fig. 3 is a plan view, parts being omitted for clearness.

Fig. 4 is a rear end elevation.

Fig. 5 is an enlarged vertical section taken along line 5—5 of Fig. 9, through one of the hopper compartments disclosing a filling unit, the valve co-operating therewith, the agitator in the hopper, and the worm feed or conveyor for delivering the hopper contents to the valve.

Fig. 6 is a fragmentary front elevation of the hopper showing the mounts for the shafts of the worms in the bottoms of the hopper thereof, together with the valve casting and the carton or container feed or conveyor.

Fig. 7 is a horizontal section taken along line 7—7 of Fig. 6 to illustrate the carton or container feed or conveyor together with the elements for holding the flaps of the carton or container.

Fig. 8 is a horizontal section taken along

line 8—8 of Fig. 2 and illustrates the measuring and filling units, the valves co-operating therewith and the carton or container conveyor or feed. 55

Fig. 9 is a vertical transverse section taken along line 9—9 of Fig. 2 illustrating the hopper construction, the worms co-operating therewith, together with the valves and the cut-off operable after filling the cartons or containers. 60

Fig. 10 is a plan elevation of the cut-off 65 co-operating with the valves.

Fig. 11 is a longitudinal section taken through the cut-off along line 11—11 of Fig. 10.

Fig. 12 is an end elevation of said cut-off. 70

Fig. 13 is a perspective view of one of the valves interposed between the hoppers and the filling and measuring units.

Fig. 14 is a horizontal section taken along line 14—14 of Fig. 1 to illustrate the mechanism for operating the carton or container feed or conveyor. 75

Fig. 15 is a similar section taken along line 15—15 of Fig. 1 to illustrate the control for the operation of the filling and measuring units from the cartons or containers. 80

Fig. 16 is a horizontal section through the shaft of the conveyor or feed for the cartons or containers showing the ratchet mechanism for advancing it. 85

Fig. 16^a is a sectional view illustrating more particularly the table supporting hub.

Fig. 17 is an enlarged plan view of the mechanism at the left of Fig. 15 for the operation of the filling and measuring units under the control of the cartons or containers. 90

Fig. 18 is a side elevation thereof with parts broken away. 95

Fig. 19 is a section along line 19—19 of Fig. 17 to illustrate the clutch mechanism.

Fig. 20 is a horizontal section taken along line 20—20 of Fig. 18 to show the clutch pin in operation. 100

Fig. 21 is a plan view of the mechanism for operating the valves.

Fig. 22 is a transverse vertical section taken along line 22—22 of Fig. 21 to illustrate the valve control mechanism.

Figs. 23, 24 and 25 are illustrations of details of the mechanisms shown in Figs. 21 and 22.

Fig. 26 is a vertical transverse section taken along line 26—26 of Fig. 1 to show the arrangement of the filling and measuring units.

5 Fig. 27 is an elevation of the valve casting showing a detail of the valve operating mechanism.

As is well known, ice cream is commercially packed in cartons or containers in 10 layers or sections of differing flavors or cartons, the numbers of layers or sections being usually three, though frequently this number is increased or decreased or a single flavor or color is packed in the carton or container. The present machine is designed to receive several flavors or colors of ice cream from the freezers in a plastic or semi-fluid condition and deliver measured quantities thereof to the cartons or containers, always 15 maintaining the various colors or flavors separate and distinct until they have been placed in the cartons or containers. Generally this is accomplished by having a hopper divided into several compartments, one of 20 which is provided for each color or flavor of cream. These compartments each have a worm screw or other conveyor in the bottom thereof by means of which the hopper's contents are continually moved toward the discharge or outlet opening centrally located 25 in the bottom thereof. A measuring and filling unit is provided for each hopper and is designed to receive and discharge a pre-determined quantity of ice cream and in order that the filling and measuring units may 30 alternately be filled and discharged a series of valves, one for each unit, is interposed between the units and the hopper, said valves alternately connecting the units to the hopper compartments and to discharge openings 35 in the valve casing. An intermittently operable conveyor or carton feed successively feeds the cartons or containers to positions below the valve casing where they receive the simultaneous discharge of the units when 40 the valves are properly positioned for this purpose. In the event it is desired to pack a single color or flavor, the hopper compartments may all be filled with ice cream of the same flavor or color, while by increasing or 45 decreasing the number of hoppers, valves and filling units the number of layers or sections packed in a single carton or container may be correspondingly increased or decreased.

50 Reference being had more particularly to the drawing, 10 designates the base plate of the machine, supported by the uprights 11 terminating at their lower ends in the spread legs 12. Mounted on this base plate 10, as 55 will be hereinafter more fully described, is a hopper H, designed to receive, if desired, three separate and distinct colors or flavors of ice cream and which for this purpose is divided by the partitions 13 into three compartments 14. Each of these compartments

14 receives one flavor or color of ice cream and as this material is placed therein from the freezer in a plastic condition, it is necessary to maintain this condition by cooling the hopper walls and thus prevent the cream from losing volume and becoming liquid. Thus in the present invention the outer walls 15 of the hopper H are double and house a continuous pipe 16 therein, which is supplied with brine through the pipe 17 passing 75 through the outer plate of one of the walls 15. In this manner, brine is circulated through the outer walls 15 of the hopper H maintaining the contents at a proper low degree of temperature, the brine escaping after circulation through the outlet pipe 18. As a suitable lid 19 is provided to cover all of the compartments 14 of the hopper H, it will therefore be seen that the hopper contents are not only protected from dust or dirt but that they are maintained at the required temperature to prevent loss of volume and a return to a liquid or fluid condition.

70 The side walls 15 and the partitions 13 of the hopper H converge toward the bottom 20 thereby making the bottom of each compartment narrower than the top, said bottoms in effect constituting the curved pockets 21 (Fig. 5) extending longitudinally of the hopper. Medially of its length 90 each compartment 14 is provided with an outlet opening 22 in the bottom thereof, the openings 22 of all of the compartments being aligned one with the other transversely of the machine. Co-operating with these outlet openings 22 is a discharge block 23 in which are formed the convergent passages 24 creating continuations of the outlet openings 22. As illustrated in Figs. 5 and 9, this block 23 enters the outlet openings 22 and 95 is embraced by the bottom of the hopper, where the latter is in part supported by said block as will be later pointed out. In order to insure the delivery of the compartment contents to the outlet openings 22 through which the contents pass to the passages 24 of the block 23, each pocket 21 has a shaft 25 extending centrally throughout the entire length thereof and projecting 100 through one end wall of the hopper where it is surrounded by a stuffing box 26 to prevent leakage. The opposite ends of these shafts 25 are enclosed in the bearings 27 formed from a plate 28 secured to the hopper end opposed to the end through which the shafts pass. The projecting ends 29 of the shafts 25 have the meshing gears 30 keyed thereto on the exterior of the hopper, whereby the rotation of one shaft rotates all 105 of the others simultaneously therewith and for this purpose one of the projecting ends 29 of the shafts is provided with an extension 29a, the free end of which is mounted in a bearing 30a carried at the upper end of 110 a vertical bearing frame 31 fastened to the 115

base or bed plate 10. At the free end thereof, the extension 29^a has a beveled gear 32 fixed thereto to which power is applied, by means of the instrumentalities to be herein-
5 after described, whereby said extension 29^a is rotated and all of the shafts 25 likewise rotated. Each shaft 25 has a pair of opposed worm conveyors or feeds 33 thereon extending from the opposite ends of the
10 pocket 21 and terminating adjoining the outlet opening 22 in the pocket bottom. Upon the rotation of the shafts 25 as aforesaid, the opposed worm conveyors or feeds of each compartment constantly bring the
15 ice cream in the pocket 21 toward and to the outlet opening 22 where it is deposited for discharge through the passage 24 of the block 23 co-operating with the opening 22 and thus the entire contents of each com-
20 partment 14 is positively delivered to the outlet opening 22 and the hopper contents are generally somewhat agitated to prevent adhesion thereof to the hopper and compartment walls.
25 To further agitate the contents of the compartments to prevent adhesion to the walls thereof, an oscillating shaft 34 is transversely mounted in suitable bearings
30 secured to the top edges of the side walls of the hopper H in central vertical alignment with the outlet openings 22 and has the paddle arms 36 fixed thereto by means
35 of the clamps 37. One arm 36 extends into each compartment and terminates adjoining
40 the pocket 21, so that as the shaft 34 oscillates, the arms swing longitudinally of the hopper compartments 14 and keep the entire mass of the contents thereof thoroughly agitated. At one terminal the shaft 34 pro-
45 jects beyond the hopper wall and there has an arm 38 fixed thereto which at its free end is pivoted to one end of a pitman 39. The opposite end of this pitman 39 is pivotally connected to a source of power which
50 is imparted through the pitman and arm 38 for rocking the shaft 34 all as will be further described.
55 After the ice cream leaves the passages 24 of the block 23, it passes to the passages 40 completely and vertically piercing the valve casing 41 disposed directly below the block 23, said passages 40 being entirely independent and forming continuations of the passages 24. The base of the block 23 has
60 a flange 23^a which rests flush against a similar flange 42 of the valve casing 41 whereby the block 23 and valve casing 41 are fastened together by bolts or other suitable fastening means 43 piercing said flanges. At one end of the valve casing 41 is a series of cylinders 44, one for each group comprising a compartment 14, a passage 24 and a passage 40, said cylinders being triangularly arranged in a unitary casting 45 though, of course,
65 it is to be understood that they may be in- dependent one of the other if desired in so far as being cast in one piece is concerned. Each of these cylinders 44 comprises a filling and measuring unit and is to receive and measure ice cream from one of the compartments 14 through one set of continuing pas-
70 sages 24 and 40 and after having received and measured such ice cream to discharge it through the passage 40 into the carton or container positioned to receive it. The uni-
75 tary casting 45 in which the cylinders 44 are formed is mounted on the integral supports 46 secured by the bolts 47 to the bed or base plate 10 in such a manner that the inner end of the casing has a water-tight fit against the valve casing 41 at the abutting flanges 48 and 49 on the casting 45 and casing respectively. As will be seen from Fig. 26, two of the cylinders 44 are arranged side by side in the casting 45 while one is disposed above and between these cylinders. Each cylinder 44 has a piston 50 mounted for reciprocation therein and operated by the piston rod 51 projecting beyond the cylinder end all of said piston rods being of the same length and designed to operate simultaneously as will be seen later herein.
80 In order to constitute a means of communication between the bore of the cylinders 44 and their respective passages 40 so that said cylinders may be alternately filled from and discharged into said passages, the latter are traversed by the tapered valve seats 52, each seat tapered from the adjoining cylinder end toward and to the opposite side of the casing where said seats are closed by the casing wall. One valve seat 52 is aligned with each cylinder 44 and at its large end opens into its co-operating cylinder. Hence, if the valve seat 52 were empty there would be a free passage from the cylinder 44 to the co-operating passage 40. However, in order to alternately connect each cylinder 44 with the upper end of its passage 40 for filling from the compartment 14 co-acting therewith and the lower end of its passage 40 for discharge into the carton or container, each valve seat 52 has a valve V mounted for oscillation therein. This valve, illus-
85 trated in Fig. 13 comprises a hollow frus-
90 trum of a cone closed as at 53 at its small end and open at its wide end or base. The closed end 53 of the valve V carries a central projecting threaded teat 55 which when the valve is located in its seat 52 pro-
95 jects through the wall of the valve casing opposed to the cylinder 44, thus registering the open end with the cylinder 44 whereby the chamber 54 of the valve is always in alignment and communication with the bore of its cylinder 44. In the wall of that part of the valve V co-extensive with the passage 40 and on one side of the axis of the valve is a port 56 adapted to form a means of communication between one end or the
100 105 110 115 120 125 130

other of the co-operating passage 40 whereby the upper end of said passage may be connected with the cylinder 44 through the chamber 54 when the port 56 faces upwardly for filling the cylinder and the lower end of said passage may be connected with the cylinder through the chamber 54 of the valve for the discharge of the previously received quantity of ice cream when the port faces downwardly. It is, therefore, clear that the valve V must be turned in order to alternately connect the cylinders 44 with upper and lower ends of the passages 40. To accomplish this, the valves are simultaneously operated by the slide bar 57 mounted for reciprocation in and across that end of the valve casing 41 through which project the teats 55 of the valves V. Each protruding end of the teats 55 has a collar 58 fixed thereto by means of the nut 59 threaded onto the teat 55, on which is formed a valve arm 60 having a slot 61 in the free end thereof (Figs. 5 and 6) and terminating adjoining the slide bar 57. The slotted ends 61 of these arms 60 enter a slot 65 formed in the slide bar 57 and receive the pins 62 arranged transversely of said bar where they are held by the thumb nuts 63 on said pins and which bear against a retaining plate 64 extending over the slotted ends 61 of the valve arms 60 and formed integrally with the slide bar 57 by the slot 65 fashioned between the bar 57 and the plate 64 as aforesaid (see Fig. 27).

From the foregoing, it will be seen that as the slide bar 57 reciprocates, the valves V will simultaneously turn with each direction of movement by the bar to alternately connect the cylinders 44 with the upper ends of the passages 40 and consequently the compartments 14 and with the lower ends of said passages 40 for simultaneous discharge into the carton or container. It will further be clear that at all times during its passage from the hopper to the carton, the ice cream from one compartment is left free and clear of the ice cream from the other compartments.

For the reciprocation of the slide bar 57 and the consequent operation of the valves V a lever 66 is pivoted to the base or bed plate 10 by means of a bearing 67 medially situated on said lever and receiving pin 68 projecting upwardly from the plate 10. The forward end of this lever 66 has a lug 69 thereon which is connected by the rod 70 with the socket 71 on the slide bar 57, so that as the lever 66 oscillates on the pin 68, the slide bar 57 will be reciprocated and the valves V operated. The rear end of the lever 66 is pivotally connected to the operating plate 72 mounted for transverse reciprocation on the bed or base plate 10 under the influence of a source of power as will be later described.

After the cylinders have discharged their

previously received contents into the carton or container through the lower ends of the passages 40 it is desirable to close the outer ends of these passages to prevent dripping and possible wastage. To that end a cut-off plate 73 is so dovetailed into the lower end of the valve casing 41 that it is free to reciprocate across the lower ends of said passage and is provided with the transverse slots 74 adapted to register with said passages when a discharge into the carton or container is taking place. At the outer end of this cut-off plate 73 is socket 75 for receiving the rod 77 whereby the cut-off 73 is connected to the depending lug 76 on the under side of the forward end of the lever 66 adjoining the lug 69. Manifestly therefore the cut-off 73 operates from the lever 66 simultaneously with the slide bar 57 so that when the valves V are in a position for a discharge from the cylinders 44, the slots 74 of the cut-off are in registration with the lower ends of the passages 40 and after the discharge are moved out of such registration.

The cartons or containers are fed or carried under the valve casing 41 by means of a conveyor or carrier which comprises a rotary circular plate or table 78 loosely mounted on an upright 79 which is mounted in the bearing 80^a of the bracket 80 attached to the bed or base plate 10 of the machine and terminates at the end of the hopper H where it acts as a support therefor. At its periphery the table 78 has a series of alternating large apertures 81 and small apertures 82 to allow for the cleaning and draining of the table, said apertures being spaced one from the other as shown and may be eliminated if desired. When the cartons are positioned on the table 78 over these large openings or apertures 81, one carton or container C is located over each opening and for the purpose of holding each carton or container C in its proper place, each aperture 81 is surrounded, except at the edge of the table or plate 78, by the outer retaining pins 83 and the inner retaining pins 84, the latter being somewhat shorter than the former. The location of these pins is such that they will embrace and receive the cartons or containers C therebetween, as illustrated in Fig. 7.

The plate or table 78 is intermittently rotated on the upright 79 to successively bring the cartons or containers C to a position in direct vertical alignment with the valve casing 41 where each carton or container is held a sufficiently long period to be filled after which it is advanced. To so intermittently operate the table or plate 78, the under surface thereof is provided with a hub 85 fixed to the table and loose on the upright 79 whereby the rotation of the hub will likewise rotate the table. The hub 85

is provided with a groove 85' (Fig. 14) in which is loosely mounted the clamp 86' of a ratchet lever 86 carrying a pawl 87 for co-operation with the ratchet gear 88 formed at the lower end of the hub and below the groove 85' (Figs. 14, 16 and 16a). The loosely mounted elements are held in place against undue rotary movement on the upright 79 by the brake band 89 embracing the hub 85 on the upright 79 and engaging the bracket 80. In order to throw the latch or pawl 87 on to the ratchet gear 88 the pawl has a rod 90 connected therewith and resting parallel to the lever 86 which has a lug 91 at its free end through which the rod 90 extends. A collar 92 is medially attached to the rod 90 and forms a bearing for one end of the coil spring 93 encircling the rod between said collar and lug 91 and thus exerts a pressure 20 on the rod toward the ratchet gear 88. It will be seen from this description that as the lever 86 is oscillated, the table will be advanced step by step to bring the cartons or containers successively under the valve casing 41 where they stop during the retrograde movement of said lever. This oscillation of the lever 86 is accomplished by the reciprocating rod 94 pivoted at one end as at 95 to the free end of said lever 30 and connected to an operating mechanism that will be described at its opposite end. To regulate and adjust the throw of the pawl 87, the rod 94 is split midway of its length into two sections adjustably connected together at the ends by the turn buckle 96, whereby the rod length may be regulated and as a consequence the throw of the pawl. Thus by regulating the throw of the pawl 87, the distance the table 78 is moved may be regulated so that the cartons or containers C may be accurately positioned with respect to the valve casing 41.

In the illustrated adaption of the present invention, the cartons or containers C are filled from the ends thereof and consequently it is necessary to hold the flaps C' and C'' of the carton or container and its liner (Fig. 6) so that they will not in any way interfere with the free passage of the ice cream into the container or carton C. This, in the case of two of the flaps, is done by the long retaining pins 83, the flaps being bent backwardly until they rest approximately flush against the carton sides before the carton is placed on the table 78 and when so placed are held bent back by the pins 83. The two remaining flaps C'' (Fig. 6) must be bent outwardly and backwardly just prior to the filling and held in this position during that operation. To accomplish this, a supporting rod 97 extends from the upright 79 where it is held by the set screw 98 piercing a collar 99 at the end of the rod and impinging against the upright to a point adjoining the valve casing 41. At its opposite or free

end the rod 97 has a sleeve 100 secured thereon for carrying the means for removing and holding the flaps C''. On one side of the sleeve 100 are the convergent somewhat resilient arms 101 extending from the ends 70 of the sleeve and carrying a tongue 102 at their point of convergence, said tongue and arms being curved to approximate the path of movement of the cartons or containers C. On the opposite side of the sleeve 100 are the spring fingers 103 forming continuations 75 of the arms 101 and extending to and beyond the valve casing 41. The arms 101 and the fingers 103 hang below the sleeve 100, as will be seen by reference to Fig. 6, and 80 the fingers 103 curve downwardly to a point below the upper end of the body of the carton C where they extend horizontally at their terminals in substantially parallel positions as at 104. A guide finger 105 is 85 formed on one of the arms 101 and projects therefrom in the general direction of the upright 79. When the carton or container has been placed on the table 78, the flaps C'' extend upwardly occupying generally the dotted line position in Fig. 6 and as the table 78 rotates, the tongue 102 enters between these flaps and under them if they happen to be bent inwardly over the end of the carton. The further rotation of the table 90 95 100 105 110 115 120 125 130 135 140 145 150 155 160 165 170 175 180 185 190 195 200 205 210 215 220 225 230 235 240 245 250 255 260 265 270 275 280 285 290 295 10360 10365 10370 10375

tated by the motor M that the entire machine is operated.

A vertical drive shaft 111 is mounted in the yoke 112 and has a beveled gear 113 loosely mounted thereon for constant rotation from the shaft 109 by means of the beveled gear 114 keyed to the inner end of this shaft 109 and meshing with the gear 113. Formed integrally with the gear 113 and on its under face is an eccentric 115 for the reciprocation of the rod 94 by means of which the table 78 is rotated, said eccentric being encircled by an eccentric band 116 attached to the rod 94 by the socket 117. Thus it will be seen that while the motor M is operating, the rod 94 will reciprocate to advance the table 78 if the pawl 87 is in its operative position.

For the simultaneous reciprocation of the piston rods 51, and hence the pistons 50, as well as the pitman 39 for swinging the agitator arms or paddles 36 a spur gear 118 is keyed to the upper end of the shaft 111 which projects above the bed or base plate 10, said gear 118 being spaced above the bed plate. This gear 118 has a crank arm 119 located above it and keyed to the shaft 111 with the gear said arm having a longitudinal slots 120 therein for adjustably mounting the crank pin 121. A collar 122 carried by a pitman 123 pivotally embraces this pin 121 so that as the gear 118 and the crank arm 119 rotate the pitman 123 will be reciprocated. The free terminals of the piston rods 51 are connected to the pitman 123 by means of the cross-head 124 slidably mounted on the upper face of the bed plate 10 all of said rods 51 being fixed to this cross-head. The end of the pitman 123 opposed to the pin 121 is pivotally connected to the cross-head 124 by means of the collar 125 engaging a pin 126 secured to the cross-head. Hence, as the gear 118 and the crank arm 119 rotate, the pitman 123 reciprocates imparting a similar movement to the cross-head 124, piston rods 51 and pistons 50 for drawing charges into the cylinders 44 and discharging the contents as heretofore described. To reciprocate, the pitman 39, its lower end is pivoted as at 129 to the cross-head 124 so that as the pistons 50 reciprocate, the paddles 36 will swing in their compartments 14.

By adjusting the stroke of the cross-head 124 and the pitman 123, the stroke of the pistons 50 and piston rods 51 will be similarly adjusted thus regulating the quantity of ice cream taken into the cylinders 44. In other words, if the stroke of these elements is increased, the quantity of ice cream is increased and, reversely, if the stroke is decreased, the quantity is decreased. In this manner, the quantity of ice cream received by the cylinders 44 may be accurately regulated and consequently the quantity of cream

in each layer packed in the carton may be thus accurately measured and determined. In order to so regulate the stroke of the pistons 50 as aforesaid, the pitman 123 is split medially and has its adjoining ends threaded and co-operating with a turn buckle 129. In this manner, the length of the pitman may be increased or decreased and as it increases, the stroke diminishes and vice versa. Of course, any change of the pitman length necessitates changing the position of the pin 121 in the slot 120 of the crank arm 119.

The operating plate 72 of the lever 66 by means of which the valves V and cut-off 73 are operated is located transversely of the bed plate 10 below the gear 118 and has a slot 130 arranged longitudinally therein for the reception of the shaft 111 passing through the plate 72 and on which the plate reciprocates. Adjoining each end of the slot 130 is a roller 131 mounted on the plate 72 for cooperation with the dog or lug 132 fixed on the under face of the gear 118 by the rivets or pins 133 passing through the ends of the dog 132 and engaging the body 90 of said gear. At one end the dog or lug 132 is beveled or cut away as at 134 for contact with the rollers 131 (see Figs. 21 to 25 incl.) As the gear 118 rotates, the dog or lug 132 contacts alternately and successively with the opposed rollers 131 and as the lug or dog is arranged obliquely to the vertical plan causes the rollers to ride successively along the length thereof thereby imparting a reciprocatory movement to the plate 72. Contact of the lug or dog 132 with one roller 131 positions the plate 72 as shown in Fig. 23 and with the other roller 131 causes it to take a reverse movement to position it as shown in Fig. 24. This movement is disclosed in Fig. 25 by the full line and dotted line positions. In this manner, the valves V are operated and the cut-off 73 is reciprocated by the oscillation of the lever 66 about its pivot 68 under the influence of the gear 118 through the plate 72.

To rotate the shafts 25 of the worm feeds or conveyors 33 by operating the extension shaft 29^a, the bearing frame 31 has a pair of vertical bearings 135 in which is mounted a shaft 136 having a beveled gear 137 at its upper end meshing with the gear 32 on the terminal of the extension shaft 29^a. At its lower end the shaft 136 has a spur gear 138 fixed thereto and meshing with the gear 118 whereby the rotation of the latter rotates the shaft 29^a and consequently the shafts 25 through the shaft 136 and the meshing gears 118, 138 and 32, 137.

From the foregoing, it will be readily understood that in order to set all of the aforesaid elements in operation, it is necessary to connect the constantly rotating gear 113 to the shaft 111 so that the latter may be rotated to operate the plate 72, the gear 130

118, the shaft 136, etc. This is accomplished by a clutch interposed between the gear 113 and the shaft 111 so under the control of the carbons or containers C that the pistons 50, 5 valves V, cut-off 73, worms 33, etc. will remain passive, irrespective of the advance of the table 78, until a carton or container is located in receiving position. A clutch collar 139 is fixed to the shaft 111 by the key 140 and is located directly below the gear 113, the eccentric 115 of said gear operating flush against the upper face of said collar. Between the shaft 111 and the periphery of the clutch collar 139 is a clutch pin socket or 10 passage 141 into which a clutch pin 142 carried by the gear 113 is adapted to drop when aligned therewith. Mounted on the upper face of the hub 113^a of the gear 113 is a clutch block 143 curved to conform to 15 the contour of the shaft and periphery of the hub 113^a and held for movement away from said gear by the guide pins 144 reciprocatingly secured in the pockets 145 formed in the gear hub 113^a parallel to the shaft 111. The upper ends of these pockets 145 are closed by the nuts 146 (see Fig. 19) threaded into the upper ends thereof and through which the guide pins 144 reciprocate. To normally retain the block 143 substantially flush against the upper face of the gear hub 113^a and hence project the clutch pin 142 into the clutch pin socket 141 of the collar 139, the pins 144 are surrounded by the retractile springs 147 bearing against the nuts 146 at their upper ends and secured to the terminals of the pins at their lower ends. Hence any movement of the block 143 away from the gear hub 113^a will 20 be against the action of the springs 147, and these springs will pull the block toward the gear 113 when the block is released for such movement. Above the gear 113, the bed plate 10 supports a depending trunnion 148 on which is loosely mounted a sleeve 149 having an operating stud 150 on one side thereof and a diametrically disposed finger 151 on the other side, the former providing a means for oscillating the sleeve 149 on the stud 148 to swing the finger 151 toward 25 and away from the shaft 111. The free end 152 of the finger 151 is curved to follow the circumference of the gear hub 113^a and is beveled on its upper edge (Fig. 18) to operate under a roller 153 projecting outwardly from the center of the clutch block 143. When the sleeve 149 is uninfluenced, the beveled end 152 of the finger 151 rests in the path of the roller 153 as it is carried by the gear 113 during its rotation and when 30 the roller contacts with the beveled end 152, it travels up the incline thereof thus lifting the clutch block 143 and so positioning and holding the clutch pin 142 that it will not enter the socket 141 of the collar 139 and the roller 153 rides on the finger 151 until the pin 142 has passed the socket 141 when it is released to allow the springs 147 to act. Hence, it is clear that shaft 111 remains stationary as long as the finger terminal 152 lies in the path of the roller 153 and this is 35 its normal position.

The sleeve 149 is oscillated successively by the cartons or containers C to swing the finger terminal 152 from the path of movement of the roller 153 whenever a carton or container is in receiving position and thus the elements operated from the shaft 111 as aforesaid are entirely inoperative unless a carton or container C is in receiving position. For this purpose a trunnion 154 is 40 suspended from the under face of the bed plate 10 adjacent the edge of the table 78 and in advance of the valve casing 41 and has a sleeve 155 loosely mounted thereon and which carries a stud 156 connected by the pitman 157 to the operating stud 150, so that as the sleeve 155 is oscillated, the sleeve 149 will be similarly moved. A lug 158 carrying a spring arm 159 extends from the sleeve 155 at right angles to the stud 156, the terminal 160 of said arm 159 being bent in the direction of travel of the cartons and in the path thereof. When a carton or container C contacts with the terminal 160 of the arm 159, the latter is moved to the 45 dotted line position in Fig. 15 which swings the finger 151 out of the path of the roller 153 allowing the gear 113 to operate the shaft 111 through the clutch pin 142. In the event no carton or container C contacts 50 with the arm 159, the elements remain passive, the roller 153 riding upon the beveled end 152 of the finger 151 lifting the pin 142 from its socket 141.

The normal position of the finger 151 is 55 in the path of the roller 153 and consequently the normal position of the arm 160 is in the path of the cartons or containers C, and these elements are retained in and returned to these positions by the spring 161 60 fastened at one end to a collar 162 fixed to the pitman 157 and anchored at the other end to a convenient part of the frame or bed plate 10 (see Fig. 8). At times, particularly for cleaning, it is desired to operate the machine independently of the cartons or containers C and to do this, it is necessary to move the members 152 and 160 against the action of the spring 161 from 65 their normal positions and hold them in 110 these abnormal positions. This is accomplished by the bar 163 slidable at one end on the pitman and pivoted at the other end to a crank arm 164 operated from a handle 165 secured to a shaft 166 mounted on the 115 under face of the bed or base plate 10 and to the inner end of which the arm 164 is also attached. The end of bar 163, slidable on the pitman 157, is moved by the handle 165, the shaft 166 and arm 164 to contact 120

125

130

with a collar 167 fixed on the pitman 157 to move the latter against the action of the spring 161 to swing the members 152 and 160 from their normal positions whereby the entire machine operates independently of the control from the cartons or containers C. Upon returning the handle 165 to its original position, the spring 161 acts on the pitman 157 to return the elements 152 and 160 to their normal positions.

The switches, etc. (not shown) for controlling the motor M are housed in a switch box 168 mounted on the bed or base plate 10 adjoining said motor.

15 The clutch mechanism of Figs. 15, 17, 18, 19 and 20, although fully illustrated and described herein, is claimed in divisional application Serial No. 697,479, filed March 7, 1924.

20 What is claimed is:—

1. The combination with a conveyor for cartons or containers, of means co-operating therewith for moving and holding the flaps of the cartons or containers, comprising a fixed finger adapted to enter between the flaps of the successive cartons or containers.

2. The combination with a conveyor for cartons or containers, of means co-operating therewith for moving and holding the flaps of the cartons or containers, comprising a fixed finger adapted to enter between the flaps of the successive cartons or containers, and arms to receive said flaps from

35 said finger and separate them.

3. The combination with a conveyor for cartons or containers, of means co-operating therewith for moving and holding the flaps of the cartons or containers comprising a fixed finger adapted to enter between the flaps of the successive cartons or containers, and arms to receive said flaps from the finger and separate them for delivery to bending and holding arms.

45 4. The combination with a conveyor for cartons or containers, of means co-operating therewith for moving and holding the flaps of the cartons or containers comprising a fixed finger adapted to enter between

50 the flaps of the successive cartons or containers, arms to receive the flaps from said finger and separate them, and spring arms receiving the flaps and bending and holding them against the carton or container body.

55 5. The combination with a conveyor for cartons or containers, of means co-operating therewith for moving and holding the flaps of the cartons or containers comprising a fixed finger adapted to enter between the flaps of the successive cartons or containers, arms to receive the flaps from said finger and separate them, and inclined arms forming continuations of the aforesaid arms

to receive, bend and hold the flaps against the carton or container body.

6. The combination with a conveyor for cartons or containers, of means co-operating therewith for moving and holding the flaps of the cartons or containers comprising a fixed finger adapted to enter between the flaps of the successive cartons or containers, arms to receive the flaps from said finger and separate them, and arms forming continuations of the aforesaid arms to bend and hold the flaps against the carton or container body.

7. The combination with a conveyor for cartons or containers, of means co-operating therewith for moving and holding the flaps of the cartons or containers comprising a fixed finger adapted to enter between the flaps of the successive cartons or containers, arms to receive the flaps from said finger and separate them, and arms forming continuations of the aforesaid arms to bend and hold the flaps away from the end of the carton or container carrying the same.

8. The combination with a conveyor for cartons or containers, of means co-operating therewith for moving and holding the flaps of the cartons or containers comprising a fixed finger adapted to enter between the flaps of the successive cartons or containers, arms to receive the flaps from said finger and separate them, and further arms for bending and holding the flaps away from the end of the carton or container carrying the same.

9. The combination with a conveyor for cartons or containers, of means co-operating therewith for moving and holding the flaps of the cartons or containers comprising a fixed finger adapted to enter between the flaps of the successive cartons or containers, arms to receive the flaps from said finger and separate them, and inclined spring arms forming continuations of the aforesaid arms for bending and holding the flaps against the carton or container body.

10. The combination with a conveyor for cartons or containers, of means co-operating therewith for moving and holding the flaps of the cartons or containers comprising a fixed finger adapted to enter between the flaps of the successive cartons or containers, arms to receive the flaps from said finger and separate them, and inclined spring arms forming continuations of the aforesaid arms for holding the flaps away from the end of the carton or container carrying the same.

11. In apparatus of the class described, a carton support having means for sustaining the carton walls against bulging, said means comprising projections of different

heights upwards from said support, certain of said projections being high enough to engage and hold certain of the carton closing flaps in open position.

- 5 12. In apparatus of the class described, means whereby a carton may be supported and advanced to a definite position, flap controlling means for bending and holding certain flaps of the carton against the carton body as the carton is being advanced to said position, and means for retaining other flaps of the carton against the carton body independently of its being advanced to said position.
- 10 13. In apparatus of the class described, means whereby a carton may be supported and advanced to a definite position, flap controlling means for bending and holding a flap of the carton against a wall of the carton body as the carton is being advanced to said position, and auxiliary means for bearing against the same carton wall to prevent its bulging due to lateral pressure resulting from the placing of material in
- 20 25

14. In apparatus of the class described, means whereby a carton may be supported and advanced to a definite position, flap controlling means for bending and holding a flap of the carton against a wall of the carton body as the carton is being advanced to said position, and retaining pins projecting upward and bearing against the same carton wall to prevent its distortion due to the lateral pressure resulting from the placing of material in the carton.

15. In apparatus of the class described, means whereby a carton may be supported and advanced to a definite position, flap controlling means for bending and holding certain flaps of the carton against the carton body as the carton is being advanced to said position, and pins projecting upward and bearing against a plurality of the carton walls to prevent their distortion due to lateral pressure resulting from the placing of material in the carton.

16. In apparatus of the class described, the combination of a hopper of considerable length having downwardly converging walls, downwardly converging partitions extending lengthwise of the hopper and dividing the same into compartments of the same length as the hopper and relatively broad at the top and narrow at the bottom, each compartment having a relatively short outlet opening in the bottom thereof substantially midway of its length, feed means in each compartment operative to feed the substance in the compartment from its ends along its bottom to its outlet opening, the openings of the different compartments being side by side, valve means cooperating with said outlet openings positioned below the hopper and having an individual pas-

sage therethrough for each compartment outlet opening, said passages terminating close together whereby the substance passing through them is fed in a plurality of closely adjacent streams into a suitably positioned container of relatively small capacity, parallel fixed cylinders positioned beneath the hopper and extending lengthwise thereof and cooperating with said valve means, pistons reciprocable in said cylinders, said valve means being operative to alternately open the passages between said compartment outlet openings and cylinders and then between the latter and the suitably positioned container, and control means for reciprocating said pistons and operating said valve means and operating said feed means concurrently in response to mechanical engagement with a properly positioned container.

17. In apparatus of the class described, the combination of a hopper, partitions dividing said hopper into compartments, said compartments having openings in their bottoms side by side, cooperating valves arranged side by side beneath said openings in position to deliver simultaneously into a single carton therebeneath, one valve being provided for each opening, similarly arranged fixed cylinders cooperating each with one of said valves, pistons reciprocable in said cylinders, said valves in one position providing communication between said compartments and cylinders and in another position between said cylinders and outlet ports above said carton, and means for simultaneously operating said valves to move them alternately into said positions.

18. In apparatus of the class described, the combination of sources of supply of the substance to be distributed, said sources having outlet openings, a valve casing associated with said openings and having an individual passage therethrough for each of said openings, a tapered valve seat for each of said passages, a hollow tapered valve mounted to cooperate with each valve seat, said valve being closed at its small end and open at its large end, and having a port in the wall thereof in alignment with the cooperating passage, cylinders communicating respectively with the open ends of said valves, pistons in said cylinders, means for reciprocating said pistons, a slide bar arranged transversely of said casing, and connections between said bar and valves whereby each reciprocation of said bar alternately aligns the ports of said valves to receive charges of the substance into said cylinders and to discharge them therefrom at a delivery point.

19. In apparatus of the class described, the combination of a hopper of considerably greater length than width having downwardly converging partitions extending lengthwise of the hopper and dividing the

same into compartments of the same length as the hopper and relatively broad at the top and narrow at the bottom, each compartment having an outlet opening in the bottom 5 thereof, said openings being side by side, valve means cooperating with said outlet openings, positioned below the hopper and having an individual passage therethrough for each compartment outlet opening, said 10 passages terminating close together whereby the substance passing through them is fed in a plurality of closely adjacent streams into a suitably positioned container of relatively small capacity, parallel fixed cylinders positioned beneath the hopper and extending lengthwise thereof and cooperating with said valve means, said cylinders being compactly arranged in a direction transverse to their axes at different distances from the hopper 15 per, pistons reciprocable in said cylinders, said valve means being operative to open communication between said compartments and cylinders and then between the latter and a suitably positioned container, and 20 means for operating said pistons and valve means in timed relation to deliver charges of the substance into the container as described.

20. In apparatus of the class described, 30 the combination of means for advancing containers in a substantially horizontal direction to a filling point, substantially horizontal cylinders and cooperating pistons positioned above said advancing means and 35 serving as measuring units, cooperating rotary valve means outside of said cylinders extending horizontally in the same direction as said cylinders and serving to guide the substance under distribution to and from 40 the same, and means for operating said advancing means, pistons and valve means in definite relation to each other.

21. In apparatus of the class described, 45 the combination of means advancing containers in a substantially horizontal direction to a filling point, substantially horizontal cylinders and cooperating pistons positioned above said advancing means and extending transversely of the line of travel of 50 the containers as they pass said filling point, cooperating substantially horizontal rotary valve means outside of said cylinders for guiding the substance under distribution to and from said cylinders, and means for operating 55 said advancing means, pistons and valve means in definite relation to each other.

22. In apparatus of the class described, 60 the combination of a hopper divided into a plurality of compartments for holding different substances adapted to be deposited in layers in a container, subjacent substantially horizontal cylinders and cooperating pistons for drawing the different substances down 65 through outlets in said hopper compart-

ments and forcing said substances side by side into a container therebeneath, and independent substantially horizontal rotary valves, one for each compartment, extending in the direction of said cylinders respectively and positioned at the juncture of said hopper compartment outlets and said cylinders respectively for controlling intercommunication from said compartments to said cylinders and from the latter to the container to be filled.

23. In apparatus of the class described, the combination of a hopper having downwardly converging walls, downwardly converging partitions extending lengthwise of the hopper and dividing the same into compartments of the same length as the hopper and relatively broad at the top and narrow at the bottom, each compartment having a relatively short outlet opening in the bottom thereof, means in each compartment operative to assist the substance in the compartment toward its outlet opening, the openings of the different compartments being side by side, valve means co-operating with said outlet openings positioned below the hopper and having an individual passage therethrough for each compartment outlet opening, said passages terminating close together whereby the substance passing through them is fed in a plurality of closely adjacent streams into a suitably positioned container of relatively small capacity, parallel fixed cylinders positioned beneath the hopper and extending lengthwise thereof and co-operating with said valve means, pistons reciprocable in said cylinders, said valve means being operative to alternately open the passages between said compartment outlet openings and cylinders and then between the latter and the suitably positioned container, and means for reciprocating said pistons and operating said valve means and said assisting means.

24. In apparatus of the class described, 110 the combination of a hopper of considerable length having downwardly converging partitions extending lengthwise of the hopper and dividing the same into compartments of the same length as the hopper and relatively broad at the top and narrow at the bottom, each compartment having an outlet opening in the bottom thereof, said openings being side by side, valve means co-operating with said outlet openings, positioned below the hopper and having an individual passage therethrough for each compartment outlet opening, said passages terminating close together whereby the substance passing through them is fed in a plurality of closely adjacent streams into a suitably positioned container of relatively small capacity, parallel fixed cylinders positioned beneath the hopper and extending lengthwise thereof and co-operating with 115

said valve means, said cylinders being compactly arranged, pistons reciprocable in said cylinders, said valve means being operative to open communication between said compartments and cylinders and then between the latter and a suitably positioned container, and means for operating said pistons and valve means in timed relation to deliver the charges of the substance into the container.

25. In apparatus of the class described, the combination of a hopper divided into compartments, each compartment having an outlet opening in its bottom, the openings of the several compartments being side by side, a valve casing beneath said openings having individual passages therethrough respectively individual to said openings, rotary valves in said casing respectively individual to said passages and having axes extending lengthwise of the hopper, parallel fixed cylinders positioned beneath said hopper and extending lengthwise thereof and co-operating respectively with said valves, pistons reciprocable in said cylinders, a reciprocating head to which said pistons are connected, said rotary valves being adapted to alternately open the passages between said compartment openings and the cylinders and then between the latter and the outlet ports of the passages, a cut off valve for opening and closing said ports, a reciprocable member movable transversely of the axes of said rotary valves and connected to said cut off valve to reciprocate it and to said rotary valves to oscillate them to establish the aforesaid passage connections, a crank disk, a pitman connecting the same to said head to reciprocate the latter and the pistons as said disk rotates, and means actuated upon the rotation of said disk to actuate said reciprocable member to operate said valves.

26. In apparatus of the class described, the combination of a hopper having downwardly converging walls, downwardly converging partitions extending lengthwise of the hopper and dividing the same into compartments of the same length as the hopper and relatively broad at the top and narrow at the bottom, each compartment having an outlet opening in its bottom, the openings of the different compartments being side by side, valve means co-operating with said outlet openings positioned below the hopper and having an individual passage therethrough for each compartment outlet opening, parallel fixed cylinders positioned beneath the hopper and extending lengthwise thereof just to the rear of said valve means, a head to the rear of said cylinders, pistons secured by piston rods to said head and reciprocable in said cylinders, a crank disk to the rear of said head, a pitman connecting said disk and head, a vertical shaft concentric with said disk, a power driven gear wheel on said shaft, clutch mechanism for connecting said gear wheel to said disk to drive the latter, connecting means between said disk and said valve means to operate the latter from said disk, hopper agitating means connected to said head to be driven therefrom, a vertical spindle forward of said valve means, a rotary table mounted on said spindle so as to bring its periphery just beneath the outlet of said valve means, a ratchet means for rotating said table, an eccentric on said power driven gear wheel, a connection between said eccentric and said ratchet means whereby said table is advanced step by step, a trip arm adjacent to the rear edge of said table, and connections extending from said trip arm to said clutch mechanism to control the latter by containers on said table.

27. In apparatus of the class described, the combination of a hopper having downwardly converging walls, downwardly converging partitions extending lengthwise of the hopper and dividing the same into compartments of the same length as the hopper and relatively broad at the top and narrow at the bottom, each compartment having an outlet opening at its bottom, the openings of the different compartments being side by side, valve means co-operating with said outlet openings positioned below the hopper and having an individual passage therethrough for each compartment outlet opening, parallel fixed cylinders positioned beneath the hopper and extending lengthwise thereof just to the rear of said valve means, a head to the rear of said cylinders, pistons secured by piston rods to said head and reciprocable in said cylinders, a crank disk to the rear of said head, a pitman connecting said disk and head, a vertical shaft concentric with said disk, a power driven gear wheel on said shaft, clutch mechanism for connecting said gear wheel to said disk to drive the latter, connecting means between said eccentric and said ratchet means whereby said table is advanced step by step, a trip arm adjacent to the rear edge of said table, and connections extending from said trip arm to said clutch mechanism to control the latter by containers on said table.

28. In apparatus of the class described, the combination of a hopper having downwardly converging walls whereby the hopper is relatively broad at the top and narrow at the bottom, said bottom having an outlet opening in it, a valve co-operating with said opening positioned below the hopper and above a delivery point, a cylinder positioned beneath the hopper and extending horizontally lengthwise thereof, a reciprocable member movable transversely of the axes of said valves and connected to said valve means to reciprocate it and to said valves to oscillate them to establish the aforesaid passage connections, a crank disk, a pitman connecting the same to said head to reciprocate the latter and the pistons as said disk rotates, and means actuated upon the rotation of said disk to actuate said reciprocable member to operate said valves.

29. In apparatus of the class described, the combination of a hopper having downwardly converging walls whereby the hopper is relatively broad at the top and narrow at the bottom, said bottom having an outlet opening in it, a valve co-operating with said opening positioned below the hopper and above a delivery point, a cylinder positioned beneath the hopper and extending horizontally lengthwise thereof, a reciprocable member movable transversely of the axes of said valves and connected to said valve means to reciprocate it and to said valves to oscillate them to establish the aforesaid passage connections, a crank disk, a pitman connecting the same to said head to reciprocate the latter and the pistons as said disk rotates, and means actuated upon the rotation of said disk to actuate said reciprocable member to operate said valves.

- rovable head to the rear of said cylinder, a piston secured by its rod to said head and reciprocable in said cylinder, a crank disk to the rear of said head, means whereby 5 said valve is operated from said disk, a pitman connecting said disk and head, a power driven gear wheel, clutch mechanism for connecting said gear to said disk to drive the latter from said wheel, a container sup- 10 port forward of said valve for holding the container at the delivery point, and means for controlling the operation of said clutch mechanism from a point adjacent to said support.
- 15 29. In apparatus of the class described, the combination of sources of supply of the substance to be distributed, said sources having outlet openings, a valve casing associated with said openings and having an individual passage therethrough for each of said 20
- openings, a tapered valve seat for each of said passages, a hollow tapered valve mounted to cooperate with each valve seat, said valve being closed at its small end and open at its large end and having a port in 15 the wall thereof in alignment with the co-operating passage, cylinders communicating respectively with the open ends of said valves, pistons in said cylinders, means for reciprocating said pistons, and means for actuating said valves to direct charges of the substance into said cylinders and to discharge the same therefrom at a delivery point.
